[57] CLAIM

The ornamental design for a tiered card holder, as
shown and described.

DESCRIPTION

FIG. 1 is a front perspective view showing the top and
one end of my tiered card holder design.

FIG. 2 is a back perspective view showing the bottom
and other end of the design.

And FIG. 3 is a view taken as indicated by line 3—3 on
FIG. 1, showing the cross sectional configuration of the
design.

FIG. 1.

FIG. 3.

FIG. 2.
